UNITED STATES PATENT OFFICE.

THOMAS ROBERT GILLETT PARKER, OF BROADHEATH, ENGLAND, ASSIGNOR TO
LINOTYPE AND MACHINERY LIMITED, OF LONDON, ENGLAND.

APPARATUS FOR PRINTING LATE NEWS IN WEB-PRINTING PRESSES OR FOR OTHER PURPOSES.

1,160,444.

Specification of Letters Patent.

Patented Nov. 16, 1915.

Application filed July 14, 1915. Serial No. 39,799.

To all whom it may concern:

Be it known that I, THOMAS ROBERT GILLETT PARKER, a subject of the King of the United Kingdom of Great Britain and 5 Ireland, and residing at Linotype and Machinery Works, Broadheath, in the county of Chester, England, have invented new and useful Improvements in or Relating to Apparatus for Printing Late News in Web- 10 Printing Presses or for other Purposes, of which the following is a specification.

This invention relates to apparatus for printing late news in web printing presses adapted to print on a plurality of different 15 webs, and it has for its object to provide means for printing late news on any of such webs, and capable of being readily adjusted as a complete entity, from one position to another, according to the particular web on 20 which the said late news is to be printed.

The invention will be hereinafter described with reference to the accompanying drawings, which illustrate, as a convenient example, a late news printing apparatus according to the present invention adapted to print on any of three different webs, receiving their main impression from three printing units located one vertically above another, Figure 1 being a side elevation and 25 Fig. 2 an elevation as seen from the right-hand side of Fig. 1, of such apparatus; and Fig. 3, a horizontal section showing certain details of the apparatus.

In order to effect the printing of late news according to one of the known methods hitherto adopted for that purpose, the particular web on which the same is to appear, after having received the main impression from the respective ordinary printing unit, 30 is led through what is known as a "fudge" apparatus, which is virtually a second printing unit, so positioned relatively to the ordinary printing unit that the impression made by it on the web will be correctly located in the column or space left for its reception. In Fig. 1 of the drawings, the three webs 1, 35 2, 3, are shown as traveling in the direction indicated by the respective arrows, from the ordinary printing units (the latter not represented in the drawings), the fudge apparatus being in position to print on the top side of the web 2. This fudge apparatus is, of itself, of known construction, and comprises as its main features an impression or

blanket cylinder 4, a fudge head or type 55 cylinder 5 coöperating with the impression cylinder, and inking apparatus 6 for inking the form on the cylinder 5. The blanket cylinder 4 is adjustable transversely relatively to the web along a shaft 7, whereon it can be secured in any position to which it may be so adjusted, by means of a clamping screw 28, Fig. 2. The other part of the fudge apparatus, comprising the fudge head 5 and inking apparatus 6, is mounted, as 60 a whole, in a frame 8, which is adjustable in opposite directions transversely of the web along a cross frame 9, this adjustment being conveniently effected by a screwed shaft 10 engaging with a nut or equivalent device 65 fast to the frame 8, and having on one end a hand wheel 11 by which it can be readily rotated. The frame 8 can be secured on the cross frame 9 in any position to which it has been adjusted by the shaft 10, by a clamp- 70 ing screw 12.

The before-mentioned shaft 7 and the shaft 13, to which latter the fudge head 5 is splined, are both rotatably supported in bearings at respectively opposite ends of the 80 cross frame 9, and these shafts are rotated in respectively opposite directions by intermeshing gears, 14 on the shaft 7, and 15 on the shaft 13, the latter shaft receiving rotary motion from a miter gear 16 fast there- 85 on and meshing with a corresponding miter gear 17 journaled in a bearing 18 fast to the frame 9, which is vertically adjustable as hereinafter described. The miter gear 17 is splined to a vertical shaft 19 so that the 90 rotative connection between these two members will be maintained for all positions of the frame 9, and consequently the shafts 7 and 13 will likewise be maintained in constant rotative connection with the said ver- 95 tical shaft 19, which latter is itself rotated by any convenient means, not represented in the drawings.

The vertically adjustable frame 9 is in dovetail connection, see particularly Fig. 3, 100 with two vertical side frames 20 rigidly secured to the floor or base of the press, and with this cross frame 9 there are engaged two vertical screws 21 threaded through nuts 22 fast on or integral with the said cross frame, 105 the arrangement being such that when the screws 21 are rotated, the vertically adjust- able frame, together with the fudge appa-

ratus mounted thereon, is raised or lowered according to the direction of such rotation. The vertical screws 21 are rotatably supported at their upper and lower ends in stationary bearings 23 fast to the side frames 20; and on the upper ends of these screws 21 are secured miter wheels 24 engaging with corresponding miter wheel 25, both fast to the same horizontal shaft 26. This shaft 26 is rotatably supported in bearings in the two side frames 20, and has secured to one end of it a crank handle 27 by which it can be conveniently rotated, and when so rotated it transmits, through the respective miter wheels 25, 24, rotary motion to the vertical screws 21 so as to effect the before-mentioned vertical adjustment of the frame 9.

As previously mentioned, the before-described fudge or late news printing apparatus is shown in position to print upon the web 2, and when it is desired that the late news shall be printed upon either the web 1 or the web 3 instead of the web 2, the crank handle 27 is rotated in the direction necessary for raising or lowering the vertically adjustable frame 9, this operation bringing the two cylinders 4 and 5 into one or other of the positions in which they are shown in dot-and-dash lines at the top and bottom of Fig. 2, it being understood that this adjustment is made before the webs 1, 2, and 3, are threaded through the machine from the ordinary printing units to the folding mechanism. The transverse adjustment of the before-described fudge apparatus along the vertically adjustable frame 9 provides for the printing of the late news in different columns of the printed web, as already well understood in the art.

If desired, suitable counterbalancing weights or other means may be provided in connection with the cross frame 9 for facilitating the vertical adjustment of the fudge apparatus, and the vertical screws, instead of being rotated by hand, may be rotated by motor. Further, instead of the vertical adjustment being effected by the before-described screws 21, this adjustment may be effected by racks and pinions, or by lifting tackle comprising cables, guide pulleys therefor, and manually or otherwise rotating the drums for winding up or paying out the said cables, in which latter arrangement there would preferably be provided a spring-controlled or equivalent locking piece for securing the frame 9 in its respective operative positions.

In cases in which the ordinary printing units (each of which is to be understood as comprising an impression cylinder and a form cylinder, indicated diagrammatically at 29, 30, and 31, 32, in connection with the respective webs 1 and 2 in Fig. 1), are not located one above another with their axes situated all in the same vertical plane,

which is the arrangement hereinbefore described as the example selected for illustration, the side frames 20 will be correspondingly deviated from the vertical so that the fudge apparatus will, when moved along those frames, be adjusted always in a direction perpendicular to the direction of travel of that part of the web on which the late news is to be printed, or, in other words, parallel with the plane containing the axis of the cylinders constituting the several printing units. Thus, assuming that the webs from the printing units travel in a vertical direction at the just-named part, then the side frames 20 would be arranged so that, when required to be adjusted for printing on a different web, the fudge apparatus would be moved horizontally. Again, in the case in which the web travels in an inclined direction at the part to be printed on by the late news printing apparatus, then the side frames 20 would be arranged so that the adjustment of the said apparatus would be in an inclined direction perpendicular to the aforesaid inclined direction of travel of the web.

From the foregoing, it will be seen that, whether the fudge apparatus be adjusted to print on the web 1, or the web 2, or the web 3, such adjustment will be effected without in any way disturbing the register between that apparatus and the ordinary printing unit, and consequently will not involve the loss of time which has been incurred in effecting a corresponding adjustment in connection with late news printing apparatus of previously known construction.

If desired, the apparatus hereinbefore described as a late news printing apparatus can, with suitable modifications, be employed for printing matter other than late news, in a distinctive color, and it is to be understood that the terms "fudge apparatus" and "late news printing apparatus" as herein employed are intended to include any such alternative use or modifications. Further, it is to be understood that instead of such apparatus being arranged to print the late news after the web has received the ordinary impressions, as has been hereinbefore assumed to be the case, it may be arranged to effect such late news printing before the ordinary printing is effected as has heretofore been proposed in connection with other late news printing devices.

Having described my invention, I declare that what I claim and desire to secure by Letters Patent is:—

1. The combination with a printing press adapted to print on a plurality of webs, of a late news printing apparatus and means adapted to adjust the said apparatus to different positions in each of which it is adapted to print on a respectively different web.

2. The combination with a printing press adapted to print on a plurality of webs, of a late news printing apparatus and means adapted to adjust the said apparatus, in a direction perpendicular to the direction of travel of that part of the respective web on which the late news is to be printed, to different positions in each of which it is adapted to print on a respectively different web.

3. The combination with a printing press adapted to print on a plurality of webs, of a late news printing apparatus, means adapted to adjust the said apparatus to different positions in each of which it is adapted to print on a respectively different web, and means adapted to adjust the said apparatus transversely of the web.

4. The combination with a printing press adapted to print on a plurality of webs, of a late news printing apparatus, means adapted to adjust the said apparatus, in a direction perpendicular to the direction of travel of that part of the respective web on which the late news is to be printed, to different positions in each of which it is adapted to print on a respectively different web, and means adapted to adjust the said apparatus transversely of the web.

5. The combination with a printing press having a plurality of printing units each comprising an impression cylinder and a form cylinder, the axes of all those cylinders being situated in one and the same plane, and adapted to print on a corresponding plurality of webs, of a late news print-

ing apparatus, and means adapted to adjust the said apparatus in a plane parallel with that containing the said axes to different positions in which it is adapted to print on 40 respectively different webs.

6. The combination with a printing press having a plurality of printing units each comprising an impression cylinder and a form cylinder, the axes of all those cylinders being situated in one and the same plane, and adapted to print on a corresponding plurality of webs, of a late news printing apparatus, means adapted to adjust the said apparatus in a plane parallel with that 45 containing the said axes to different positions in which it is adapted to print on 50 respectively different webs, and means adapted to adjust the said apparatus transversely of the web.

7. The combination with a printing press having a plurality of printing units, each comprising an impression cylinder and a form cylinder, adapted to print on a corresponding plurality of webs, of a late news 60 printing apparatus, and means adapted to adjust the said apparatus to different positions in each of which it is adapted to print on a respectively different web while maintaining the register between that apparatus 65 and the respective printing units.

In witness whereof I have hereunto set my hand in the presence of two witnesses.

THOMAS ROBERT GILLETT PARKER.
